JOHN RICHARDSON AND FREDERICK H. STEVENS, OF NEW YORK, N. Y.

Letters Patent No. 66,254, dated July 2, 1867.

IMPROVEMENT IN MACHINES FOR BUNDLING KINDLING-WOOD.

The Schedule referred to in these Letters Patent and making part of the same.

TO ALL WHOM IT MAY CONCERN:

Be it known that we, JOHN RICHARDSON and F. H. STEVENS, of New York city, in the county of New York, and State of New York, have invented certain new and useful Improvements in Machines for Bundling Kindling-Wood; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in a novel construction of a machine, so arranged as to receive the wood properly prepared, and bind it into bundles suitable for the market, and in which the operations are performed automatically or wholly by the machine.

Figure 1 is a top plan view.

Figure 2 is a front end view, and

Figures 3, 4, 5, 6, 7, 8, and 9 are views of portions shown more in detail.

In the drawings, A represents the bed or frame of the machine, made in any suitable manner. On this frame we locate a metal tube, B, having its rear end brought to a sharp edge, as shown at *a* of fig. 6, so that when a bundle of wood is shoved into it from the rear, the sharp edge will split off and separate such portion of the sticks as may be outside of the tube. This tube may be made with its sides parallel, except where bevelled off on the inside to sharpen the edge; or it may be made conical throughout a part or the whole of its length, and have its rear end brought to an edge by beveling on its exterior, or partly on its exterior and partly on its inside. Directly in rear of the tube B is located a sliding plunger or follower, D, to which a reciprocating motion is imparted by a crank, *b*, attached to the driving-shaft G, the follower D being so arranged as to draw back far enough to permit an endless belt, C, or other wood-carrier, to pass between the follower and the rear end of the tube B for the purpose of delivering the wood to the tube at intervals, as hereinafter explained. The driving-wheel E of the machine is mounted on a sleeve or hollow shaft, F, which turns loosely on shaft G, which shaft F is intended to be continuous in its motion, while the shaft G is to operate only at stated intervals. To accomplish this, a rigid arm, H, is secured to the shaft G, and extends alongside of the wheel E, as shown more clearly in fig. 8. On the side of the wheel E is pivoted a dog, *c*, having one end pressed inward by a spring, *c'*, this dog being so located that when the wheel revolves, the dog, unless tripped by lever *d*, will engage or lock against the arm H, and thereby cause the shaft G and all its attachments to rotate with the wheel E and sleeve F. This tripping-lever *d* is so located that, as the wood-carrier C is brought between the bundling tube B and follower D, it will be thrown aside out of the way of the dog *c*, and thus permit the dog to engage with the arm H, and cause the shafts F to revolve in connection with shaft G, thereby imparting motion to the crank *b*, which will shove the follower D forward, and drive the wood on the carrier C into the open end of tube B. As soon as this is done, the lever *d* is thrown back to its original position by the spring *d'*, fig. 1, and as the dog *c* comes around again it will be tripped by the end of lever *d*, thereby permitting the wheel E, with its loose-shaft F, to go on, while the follower D and the wood-carrier C, together with all those parts driven by the shaft G, remain stationary long enough to permit the bundle of wood that has been shoved into the tube B to be bound, as hereinafter explained.

There are various ways in which the wood-carrier may be constructed and operated. In fig. 1 it is represented in the form of an endless belt, C, having a series of boxes, C¹, open at each end mounted on it, the form of the boxes being either octagonal, as represented in fig. 2, or otherwise, as may be preferred. In case this form is used, it will be operated by connecting it in any suitable manner with the driving part of the mechanism. In fig. 3 a different plan is represented, in which we use a box, C², open at the front and top, sliding back and forth loosely on plate C³ by means of bolts passing through slots *a'*. This plate C³ has a reciprocating motion in a direction at right angles to C², it being guided in a similar manner by slots *e'* formed in the bed on which it rests, it being operated by a rod, *f*, connecting it to an elbow-lever, L, which, in turn, is connected by a rod, L¹, to a standard, L², pivoted at its lower end to the bed A, and against which a cam, I¹, on shaft F presses, as shown in fig. 1, a spring, M, serving to restore the parts to their original position as soon as the cam I¹ ceases to press on the rod L¹ or standard L². The wood is placed in the box C² by the attendant, who then shoves it

back on plate C³, so that the raised shoulder or block a² shall engage with its outer end, and as the plate C³ is drawn forward between the tube B and the follower D, it carries the box C² with it, thereby bringing the wood in proper position to be shoved into the tube B. On the rear side of the box C² is a projecting pin or arm, a³, which, as the box is drawn forward, strikes against the end of lever d, throwing its rear end out of the way of the dog e, thus permitting the dog e to engage with the arm H, and thus set the follower D in motion to shove the wood into the tube B. As soon as the cam I¹ lets the carrier return, which it does before the dog e and arm H have made an entire revolution, the lever d returns to its original position, and, as the dog e comes to it, it is tripped by the end of lever d, thereby permitting the shaft G and its attachments to remain stationary, while the sleeve F, with its attachments, continues its motion.

After the wood is thus placed in the bundling tube B, the next operation is to bind it and remove it from the tube. For the purpose of binding it, we locate at the front part of the machine a drum or reel, I, carrying a supply of small-sized annealed wire, e², which is fed by friction-wheel J up through a steel tube, e³, inserted in the flange of tube B, as shown in fig. 2. This feeding is effected by means of the bevelled gear A¹ on the end of shaft G, connecting with shaft A², which latter, by similar gear, A³, drives shaft A⁴, which, in turn, imparts motion to the feeding-wheel J. It is obvious, however, that the feeding mechanism may be operated by any other suitable arrangement of mechanism, the principal requisite being that it shall be so arranged as to feed the wire only at the proper intervals; and for this reason it is driven from the shaft G, which, as previously explained, operates only when its arm H is engaged by the dog e on wheel E. For the purpose of regulating the feed of the wire e², a friction-block, K, is pressed against the periphery of the feed-wheel J by a spring, as shown in fig. 2, an additional wheel, J¹, being used, if desired, to assist in guiding the wire to the tube e³. In the front face of the tube B, on one side, a notch or recess is formed to receive the end of the mandrel M, which is to twist and cut off the wire after it has been passed around the bundle of wood, as will be presently explained. The tube e³, through which the wire is forced by the feeding apparatus, has its upper end terminating just at or slightly above the surface of the lower side of the recess in the front of tube B, and has its end hardened and made sharp on its inner edge, to act as a stationary shear-blade to cut off the wire when the latter is pushed against it, by the turning of mandrel M, as hereinafter described. The mandrel M is mounted on the front end of the frame A in suitable bearings, in such a position as to cause its end next the tube B to rest in the recess in the side of said tube, and directly over the end of the small tube e³, through which the wire passes, there being a notch or recess formed in the end of the mandrel M for the wire to pass through as it emerges from the small tube e³. The mandrel M is made hollow or tubular for a portion of its length, as shown in section in fig. 6, and has inserted loosely within it a rod, h, which has a recess cut in its side near its outer end, so as to form a head, i, on its outer end, as shown, which, when drawn back within the mandrel, will clasp and hold the wire tight, the wire passing through the recess in the end of the mandrel, and also that in the side of the rod h, simultaneously, the mandrel and rod being so arranged that when the rod is shoved out, the opening in each for the passage of the wire will be in line with each other. The rod h is moved out and in by means of a pin, j, inserted rigidly in rod h, and working loosely in a spiral slot cut in the side of the mandrel, as represented in fig. 1, this pin being arranged to strike against the end of a pivoted catch or dog, k, when the motion of the mandrel is reversed, as hereinafter explained.

On the mandrel M are mounted two loose bevel-gears O¹ and O², to which motion is imparted by a similar gear, O, on the end of shaft N¹, which, in turn, is driven by bevel-gear N on sleeve F, as shown in fig. 1. On the mandrel, and between the gears O¹ and O², is placed a sliding clutch, P, so attached to the mandrel as always to revolve with it, there being sufficient space between the gears O¹ and O² to permit the two latter to revolve without touching the clutch, in which case the gears would revolve in opposite directions, while the mandrel, with the clutch P, would remain stationary, which it does while the wire is being fed in and passed around the bundle of wood in tube B. By throwing the clutch P into connection with gear-wheel O¹, the mandrel will be made to revolve in one direction, and when the clutch is shifted so as to engage with the gear O², then the mandrel will be made to revolve in the opposite direction. This shifting of the clutch P is effected by means of an oscillating arm, P¹, pivoted below the mandrel at the front of the frame A, as shown in fig. 2, this arm P¹ being operated by having one end of its horizontal arm connected to an elbow-lever, Q, shown in fig. 7 detached, and in fig. 1 in place. A rod, R, connects this elbow-lever Q with a standard, R², pivoted to the frame A in such a position as to be operated by a cam, R³, on the shaft G, as shown in fig. 1. When the cam R³ strikes the arm R², and, through the medium of rod R, operates the elbow-lever Q, the arm P¹ is thereby tipped so as to throw the clutch P into connection with gear O², but after the point of the cam R³ has passed, a spring, m, serves to draw the rod R back again, thereby operating to throw the clutch P in the opposite direction, and causing it to engage with the gear O¹.

As it is necessary to time the movements of this clutch, so as to reverse the motions of the mandrel M at certain intervals, we apply for that purpose the device represented in fig. 7. This consists of a disk, R, secured loosely to the standard, directly under the outer end of the mandrel M, and having a series of teeth, o¹, formed on a part of its periphery, and having also a notch, n², cut in its edge, as shown. A spring, l, has one end attached to the disk R¹, its opposite end being coiled around and secured to the stud or axis on which the disk turns. A cog or projection, n, on the mandrel M is so arranged as to engage with one of the teeth o¹ at each revolution of the mandrel, thereby causing the disk to revolve until the notch n² comes opposite the pin n¹ on lever Q, when said pin n¹ falls into the notch n², which permits the spring n on rod R to tip the shifter or arm P¹, and thereby throw the clutch into connection with gear O¹. When the cam R³ shoves the rod R forward, the pin n¹ is drawn out of the notch n², which releases the disk, and instantly the spring l returns the disk R¹ to its original position ready for a repetition of the operation. By inserting a pin in any of the holes o in said disk, the distance that it will be thrown back by the spring can be regulated, as said pin, coming in contact with the

standard, will not permit the disk to move further; and in this way the number of revolutions made by the mandrel M is also regulated, as it is obvious that it will rotate as many times as there are teeth o^1 brought into position to be hit by tooth n^1 before the notch n^2 arrives opposite the pin n^1 , when the clutch is shifted and the motion is reversed. When the wire has been twisted, and thus made secure by the revolving of the mandrel, it must be released in order to permit the bundle to be shoved out of the tube B, and this is done by the shifter P¹ throwing the clutch into connection with gear O¹, which reverses the motion of the mandrel, and in so doing brings the pin j against the end of the pivoted dog k , which latter permits the pin j to pass in one direction, but stops it when moving in the opposite direction. As the mandrel revolves, and the pin j is prevented from revolving by dog k ; the pin is drawn along the spiral slot in the mandrel, thereby pushing the rod h outward and causing the lip i to release its hold on the wire.

In order to bring the clutch P to a position midway between the gears O¹ and O² on the mandrel, so as to let the mandrel remain stationary while the wire is being fed in and passed around the bundle, an eccentric, u , is placed on the mandrel, and connected by a rod, t , fig. 2, with the arm v of the shifter P¹, the eccentric being so located on the mandrel as to move the clutch and disconnect it from gear O¹ at the instant the pin j has reached the outer end of the curved slot, the clutch being then in such a position on the mandrel as not to connect with either gear O¹ or O², thus permitting them to revolve loosely on the mandrel, while the latter stands still. In order to adapt the machine to the bundling of wood of different lengths, we use an eccentric crank-pin on the crank that operates the plunger D, the form of this crank-pin being shown in fig. 1. By turning this pin in its seat in the arm b , the length of the stroke of the crank may be changed at pleasure. By this construction and arrangement of parts we produce a machine that requires but a single attendant to fill the carrier with wood and shove it back, when all the subsequent operations are performed automatically at their proper times. We are thus enabled to perform the labor in a very speedy and efficient manner.

Having thus described our invention, what we claim, is—

1. The use of a tube, having its end provided with a sharp edge, and having its interior slightly conical, for the purpose of receiving, shaping, and holding the bundle, substantially as described.
2. The combination of the driving-wheel E, mounted on the tubular shaft F, with the arm H, secured to the shaft G, and the lever d, or its equivalent, arranged to trip the dog e, and to be operated by the wood-carrier as the latter brings the wood to the bundling tube B, substantially as set forth.
3. The wire-clasping and twisting device, consisting of the mandrel M and the sliding-rod h, provided with the lip i, or its equivalent, when arranged to operate as and for the purpose set forth.
4. Regulating the twisting of the wire and the shifting of the clutch by means of the disk R¹, operated by the mandrel and returned by the spring l, substantially as described.
5. The combination of the mandrel M, bevel-gears O¹ and O², sliding-clutch P, eccentric u, and arm P¹, arranged to operate as and for the purpose set forth.
6. The combination of arm P¹, elbow-lever Q, and disk R¹, arranged to be operated by cam R³, or its equivalent, in connection with the movement of shaft G, for the purpose of moving the clutch P at the desired time, substantially as described.
7. The tube e³, having its end arranged to operate in connection with the edge or lip of the recess in the end of the mandrel, through which the wire is fed, for cutting off the wire by a shear-cut, as set forth.
8. The wood-carrier, consisting of the sliding-box O², mounted on the reciprocating plate O³, when arranged to operate substantially as described.

JOHN RICHARDSON,
FREDERICK H. STEVENS.
